LEWIS H. SONDHEIM, OF NEW YORK, N. Y.

PENCIL.

1,158,736.

Specification of Letters Patent.

Patented Nov. 2, 1915.

Application filed December 2, 1914. Serial No. 875,123.

To all whom it may concern:

Be it known that I, LEWIS H. SONDHEIM, a citizen of the United States, residing in the city of New York, county and State of New York, have invented a new and Improved Pencil, of which the following is a full, clear, and exact description.

The invention relates to that class of pencils in which the lead is projected beyond the casing according as new writing points are required, and provision is also made for permitting the lead to be pushed back within the case whenever desired.

The object of the invention is to provide an inexpensive pencil of light weight, which may be operated without complicated movements, and I attain this object by using only one tube in the interior of the casing and by constructing said tube and the pusher 20 which is actuated by the same—and which in turn acts upon the lead—in such manner that the lead may be projected or fed forward and then held in its advanced position by the simple forward and rearward movement of the outer actuating parts of the pencil, which separate lateral movement of said outer parts, distinct from said feeding movement, is provided to release the pusher and the lead when the latter is to be returned 30 within the casing by pressure upon the lead-point.

Reference is to be had to the accompanying drawings, forming a part of this specification, in which similar letters of reference indicate corresponding parts in all the figures.

Figure 1 is a side view of a pencil embodying my invention, the parts visible being in the normal position showing the pencil ready for use.—Fig. 2 is a sectional elevation showing the parts in their position at the finish of a lead-advancing move prior to their being returned to their normal position.—Fig. 3 illustrates a modification in the construction of the casing, the same being extended by the attachment of a metal ferrule. Fig. 4 is a view of the rear portion of Fig. 1, showing the recess in the casing which in practice is covered by the sleeve.—Fig. 5 is a similar view of the rear 50 portion of Fig. 3.—Fig. 6 is a view of the front and rear ends of the lead-containing actuating tube, showing part of the series

of recesses in same. Fig. 6^A shows the reverse side of said tube with its wide longitudinal slot.—Fig. 7 is a sectional elevation of a portion of the pencil showing a modification by the use of a coiled spring.—Fig. 8 is a cross section of the pencil, taken on the line x—x in Fig. 2 and showing the pusher-pawl resting in one of the recesses of the actuating tube. Fig. 8^A is a similar cross section but showing the tube rotated from its position in Fig. 8, and the pawl resting upon a solid portion of said tube. Fig. 9 and Fig. 9^A show modifications of the method of preventing the pusher from moving transversely. Fig. 10 is a sectional elevation showing the construction of the pusher and pawl, and Fig. 10^A shows a metal blank from which the body of the pusher is formed.—All the figures except the last are shown more or less enlarged.

The casing or shell A is preferably made of wood tapered at the forward end and has a longitudinal bore B to receive the lead F and its holding and adjusting mechanism, presently described. At the tapered end of the case the bore B is of such width as to exert a slight friction upon the lead. Opposite the point where the tapered end merges into the cylindrical part of the case the bore widens, and from this point there is a longitudinal groove C which communicates with the bore B and extends to the rear of the casing as shown in Figs. 1, 8, 9 and 10. In the preferred form of the invention the bore B widens still farther near the rear end of the pencil to accommodate an eraser as shown in Fig. 2, or to accommodate an eraser and a coiled spring as in 90 the modification shown in Fig. 7.

In the bore B is placed an actuating tube D having a longitudinal slot d as shown in Fig. 6^A and a series of recesses d' ranging lengthwise of said tube approximately opposite the slot d (Fig. 6).—Said tube close to its rear end has the pin holes d² through which the pin d³ passes as shown in Figs. 2, 6 and 7.

It is obvious that in place of recesses cut 100 out from the material of the tube D for the purpose of providing surface edges upon which the end of the pusher-pawl may rest, such edges can be produced in other man-

ner, as for instance by a stamping process mentioned in Patent No. 469,754 issued to me March 1, 1892 and shown there in Fig. 6 of the drawing. The lead F fits the tube 5 so that, while it is prevented from shaking therein, it will not frictionally bind it.— Within the actuating tube D is loosely fitted a pusher E consisting of a body (formed from a blank of spring sheet metal of the 10 shape shown in Fig. 10^a) and a pawl e^4 as shown in Fig. 10. The forward part of the pusher, e' , which abuts the lead F, has tubular form, while the rear part e^2 , connected therewith by the narrow strip e^3 has 15 the form of a U the ends flaring slightly outward, and these ends when compressed into the groove C will exert a containing hold upon the side walls of said groove sufficient to hold the pusher in its position while the 20 tube D is moved rearward and also to prevent said pusher from moving transversely in the casing when the tube D is turned.

As I consider the combination of a transversely stationary pusher provided with a 25 spring pawl and an actuating tube having a wide slot through which a part of the pusher projects, the tube being adapted to be turned partly around said protecting part so as to change the relative transverse position of the tube and the pawl, as a material 30 part of my invention, I have shown modifications in Fig. 9 and Fig. 9^a by which this relative movement may be attained by means differing from those shown in the preferred 35 form.

Another feature, which I consider as a material part of my invention is the construction of the actuating tube D, which differs from the tube used in Patent No. 40 426,742 granted to me April 29th 1890, in having the series of recesses, which provide pawl-engaging surface shoulders, placed opposite or approximately opposite the position 45 of the wide longitudinal slot of said tube, as it would be practically impossible to use a tube, as shown in said former patent, through the longitudinal slot of which the connecting element between a part of the pusher and a part of the pencil-casing (necessary to restrain the pusher from rearward 50 movement with the receding tube) has to project, together with a spring-pawl so placed as to engage the teeth or recesses which in the former construction adjoin one 55 edge of said slot.

The pawl e^4 is formed of a piece of spring wire which is firmly held in the tubular part of the pusher, its forward part e^5 , which extends through and beyond the part e^2 of 60 said pusher, being of diminished size so as to be flexible, and its end e^6 is bent to form a detent.

Surrounding the outside of the casing A near its end (or its metallic continuation A'

when such is employed) is placed a sleeve 65 G, preferably of sheet metal, which at or near its center has the pin holes g' on opposite sides, said sleeve being so fitted as to be easily slid and also rotated upon the casing.—The casing near said rear end has the 70 oblong recesses H which extend from side to side thereof, and which in practice are covered by the sleeve G. The extent of said recesses lengthwise may correspond to the distance which either two or three of the series 75 of recesses d' occupy upon the tube D, inclusive of the spaces between them, and their extent laterally is so measured that the pin d^3 can travel a distance approximate to the width of the slot d of the tube D. 80

The pin d^3 passes through the pin holes of the sleeve G, through the recesses H and through the holes d^2 of the tube D and is fastened in any manner so that it cannot fall out. The relative position (laterally) 85 of the groove C with the recesses H is such, that when the pin d^3 is located at that side of the recess H where it is shown in Fig. 4 (and which for brevity I will call the "right-hand" position) the corresponding 90 positions of the sleeve G and tube D will place the recesses d' of said tube in line with the spring end and detent e^6 of the pusher pawl, while if the sleeve is rotated so as to carry the pin d^3 to the opposite side (as 95 shown in the equivalent H' of the recess H in Fig. 5—and which I will call the "left hand" position) the point of the pusher pawl will have been pressed into the sharp corner of that recess d' in which it had been 100 resting, and thence under the surface of the tube d and will then be in line with the unbroken range of metal at the side of the recess-points.

In the modified form, as shown in Figs. 105 3 and 5, the rear end of the casing is extended by the addition of a metal ferrule A' which is immovably attached to the casing in such way that its outer surface will be in line with the surface of the wooden 110 part. In this form it will be possible to use either a recess H of the shape shown in Fig. 4, or to substitute for it a "bayonet joint" recess H' as shown in Fig. 5, the objection 115 to the use of the latter shape in a wooden part being the liability of the bordering part of the case to break. In either shape of recess the sleeve G, pin d^3 and tube D can be moved lengthwise in the "right-hand" position, and can be rotated to the "left hand" 120 position when required, the difference being merely that movement lengthwise in the "left hand position," which would be without practical effect, would be estopped when the recess was of the shape H'. 125

I have shown the construction of the preferred form of the invention without the employment of the coiled spring which is gen-

erally used in automatic pencils, and the sleeve G after being pushed forward has to be drawn back by hand, and this method is also preferably used in the modification 5 shown in Figs. 3 and 5. However, if desired, a coiled spring may be used in either case to return the sleeve G and the parts attached thereto to their normal position (lengthwise) as shown in Fig. 7, the forward end of the spring I resting upon a shoulder a' in the casing A, and its rear end upon a washer d' which latter rests upon the pin d'' .

In Fig. 9, I show a modification of the 15 manner of preventing the pusher from being caused to co-act with either the rotary movement or the rearwardly longitudinal movement of the tube D by friction between said two elements. In place of the wide 20 groove C there is a narrow groove or slit C', and in place of the two flaring parts e^2 of the pusher there is a simple rib e^7 which is attached lengthwise to the rear part of the body of said pusher, which—in this construction—may be of tubular form throughout its length, the rib e^7 being of sufficient thickness to have a jamming hold between the opposite sides of said slit, so that the pusher will move longitudinally only when 25 30 forcibly pushed, and cannot move transversely at all.

In Fig. 9^a, I show a further modification with the same object as in Fig. 9.—There is a long strip g (preferably of metal) inserted in the casing which projects slightly 35 into the bore B and into the slot of the tube D. The tubular body of the pusher at its rear part is provided with a rib e^8 which enters the slot of the tube D, and which has 40 a narrow slit e^9 into which the strip g enters and wherein it has sufficient retaining hold to prevent movement of the pusher except when the latter is forcibly pushed in a longitudinal direction.

45 It is obvious that still other means may be used for causing a frictional engagement of a part of the pusher with a part of the interior of the shell, of sufficient potency to prevent the pusher from being carried rearward by accidental friction with the rearwardly moving tube, while said pusher is held transversely stationary during the rotation of the tube by unyielding lateral contact of one of its parts with a resisting part of 50 55 the shell; and I consider any method of attaining the combination of these respective functions—relative to the pusher—by equivalent means as within the scope of my invention.

60 The operation of the pencil is simple.— When a long lead has first been passed into the bore B and into the tube D from the point of the casing and the pusher carried rearward (the sleeve, pin d'' and tube being

in the "left-hand" position) the sleeve is 65 rotated to the right hand, the pin d'' during such rotation resting upon the rear edges of the slots H (or H'). The end e^6 of the pusher-pawl will then be in line with the series of recesses d' of the tube D. 70

If it is now desired to advance the lead the sleeve G is pushed forward and then drawn back, and this movement is repeated until a desired length of lead point has been projected. During the forward movement 75 the point of the pawl which either was already in engagement with the rear edge of one of the recesses d' , or has engaged such recess during the first part of the forward movement of the tube D (which co-acts with 80 the sleeve G) is moved forward and the tubular part e' of the pusher which abuts the lead F projects said lead through the point of the casing, the holding power which the pusher has through the frictional contact of its flaring parts e^2 with the sides of the groove C being overcome by the direct force exerted in the movement. During the return move of the sleeve to its former position and the consequent rearward move of 85 the tube D, the pusher is held stationary by the mentioned frictional holding power of its parts e^2 which overcomes any slight incidental friction of the tube upon the pusher, while the point of the pawl rides over the 90 intervening recesses d' . When it is desired to move the lead rearward, the sleeve H is rotated to the "left hand" position, turning the tube D in the same direction.—As the pusher E is held against lateral movement 100 by the jamming confinement of its parts e^2 in the groove C, the pawl-point e^6 is forced under the surface of the tube D (as described before) and out of line of the recesses d' , and pressure upon the lead point 105 will cause said pusher to slide rearward in the tube D until the projecting part of the lead has been pushed into the casing, or until the pressure is discontinued.

I do not limit myself to the details of 110 construction I have shown, as certain parts may be slightly changed without departing from the spirit of my invention.—

Having described my invention, I claim: 115
 1. In a pencil the combination of an outer shell having a central bore, a longitudinally reciprocating and rotatably movable lead containing tube in said bore, provided with a longitudinal slot and a longitudinally arranged series of recesses forming pawl-engaging surface shoulders, a pusher within 120 said tube provided with a spring-pawl to engage said pawl-engaging shoulders when the pawl is in line with them, the interior of the shell and the pusher being respectively provided with means which co-act one with the other to restrain the pusher from turning in said shell, one or the other pass-

ing the exterior surface of the tube through its slot for the purpose, the slot of the tube being of sufficient width to allow the tube to have a turning movement relatively to the pusher to bring the end of the pawl out of engagement and again into engagement with the surface shoulders of said tube.

2. In a pencil the combination of an outer shell having a central bore, a lead containing longitudinally reciprocating and rotatably movable tube in said bore provided with a longitudinal slot and a longitudinally ranged series of recesses forming pawl-engaging surface shoulders, a pusher within said tube provided with a spring-pawl to engage said pawl-engaging shoulders, the interior of the shell and the pusher being respectively provided with means which co-act one with the other to restrain the pusher from being carried rearward by frictional contact of its body part or its pawl with the tube during the rearward movement of said tube, one or the other of the mentioned means passing the exterior surface of the tube through its slot for said purpose.

3. In a pencil the combination of an outer shell having a central bore and an inner longitudinal groove communicating with the bore, a longitudinally reciprocating and rotatably movable lead containing tube having a longitudinal slot and a series of recesses forming pawl-engaging surface shoulders, a pusher within said tube provided with a spring-pawl to engage said shoulders and also provided with a member extending through the slot of the tube into the mentioned groove to engage the walls of same so as to prevent the pusher from lateral movement in the shell, the slot of the tube being of sufficient width to allow the tube to have a turning movement relatively to the pusher to bring its spring-pawl into and out of engagement with the shoulders of the tube.

4. In a pencil the combination of an outer shell having a central bore and an inner longitudinal groove communicating with the bore, a lead containing longitudinally reciprocating and rotatably movable tube therein having a longitudinal slot and a series of recesses forming pawl-engaging surface shoulders, a pusher within said tube provided with a spring-pawl to engage said shoulders and also provided with a member extending through the slot of the tube into the groove of the shell, said member having a frictional contact with the walls of said groove of greater potency than the frictional contact of the pusher with the tube while its pawl is riding over the said shoulders during the rearward movement of said tube, whereby the pusher will be kept stationary in the shell during said rearward movement of the tube.

5. In a pencil the combination of an outer

shell having a central bore and an inner longitudinal groove communicating with said bore, a longitudinally slotted lead containing tube within said bore and a pusher within said tube having a member extending through the slot of the tube into the groove of the shell, said member having a jamming engagement with opposite walls of said groove and thereby holding the pusher against being moved either transversely or in a longitudinal rearward direction by the frictional contact of the moving tube, means to actuate said tube from the outside of said shell to rotate said tube and to move it forward and rearward and means to propel the pusher in a forward direction by the forward movement of the tube.

6. In a pencil the combination of an outer shell having a central bore, a longitudinally reciprocating and rotarily movable lead containing tube in said bore, provided with a longitudinal slot and a series of recesses, forming pawl-engaging surface shoulders, ranging lengthwise of said tube opposite its longitudinal slot, a pusher within said tube provided with a spring-pawl to engage said surface shoulders when the pawl is in line with them, the interior of the shell and the pusher being respectively provided with means which co-act one with the other to restrain the pusher from turning in the shell and also from being carried rearward by frictional contact with the tube one or the other of said co-acting means passing the exterior surface of the tube through its slot for this purpose, the slot of the tube being of sufficient width to allow the tube to have a turning movement relatively to the pusher to bring the end of the pawl out of engagement and again into engagement with the surface shoulders of said tube, and means to impart a rotary as well as a reciprocating longitudinal movement to said tube from the exterior of the shell.

7. In a pencil the combination of an outer shell having a central bore and an inner lengthwise groove communicating with said bore, a longitudinally and rotatably movable lead containing tube in said bore, provided with a lengthwise slot and a series of pawl-engaging surface shoulders ranging lengthwise of said tube, a pusher within said tube provided with a spring-pawl to engage said surface shoulders when the pawl is in line with them, and having a member extending through the slot of the tube into the groove of the shell to hold the pusher against being moved transversely, said outwardly extending member of the pusher also having means for frictional engagement with parts of the interior of the shell of greater potency than that, which may be exerted by the incidental contact of the pusher with the tube, thereby preventing said pusher from

being carried rearward by the tube, the slot of the tube being of sufficient width to allow said tube to have a turning movement relatively to the pusher, to bring the end of the pawl out of engagement and again into engagement with the surface shoulders of said tube, and means to impart a rotary as well

as a reciprocating longitudinal movement to said tube from the exterior of the shell.
